LEO J. GRUBMAN, OF BELLE HARBOR, NEW YORK, ASSIGNOR TO VOICES, INCORPORATED, OF NEWARK, NEW JERSEY, A CORPORATION OF DELAWARE.

SOUNDING REED FOR CRIERS, VOICES, AND OTHER SOUND-PRODUCING DEVICES.

Application filed February 11, 1927. Serial No. 167,435.

This invention relates to sounding reeds for criers, voices and other sound producing devices such as are used in connection with dolls or other toys, and more particularly relates to certain improvements in the sounding reed construction heretofore invented by me and shown and described in Patent No. 1,590,188, issued June 29, 1926.

It is the primary object and purpose of my present improvements to materially simplify and reduce the manufacturing cost of such reed constructions and expedite the assembly of the several parts thereof with positive security of the vibratory sound producing element against possible displacement with relation to the ingress end of the reed channel or passage.

To the above end, the essential features of my present improvements, in a preferred embodiment thereof, consist first in the provision of a sheet metal plate or wall having a dished section with parts struck or angularly offset out of the plane thereof to provide a sound passage having an egress end opening upon one side of the wall and said channel or passage being open upon the opposite side of said wall for the ingress of air thereto and communicating with a relatively shallow recess formed in said wall in which the vibratory reed element is positioned. The free end of this element is positioned over the ingress side of the sound channel or passage, said element extending longitudinally in said recess and having an opening at its other end registering with an opening in said plate or wall. A resilient sheet metal strip has a hollow stud struck therefrom and projected through said openings and clinched upon said wall or plate to thereby permanently fix the vibratory element in position, said sheet metal strip at its other end bearing upon said element to yieldingly hold the free end thereof in a normal position relative to the ingress end of the sound channel and limiting the extent of vibratory movement thereof.

With the above and other objects in view, the invention consists in the improved sounding reed and in the form, construction and relative arrangement of the several parts thereof as will be hereinafter more fully described, illustrated in the accompanying drawings and subsequently incorporated in the subjoined claims.

In the drawings, wherein I have illustrat-

ed one simple and practical embodiment of my invention, and in which similar reference characters designate corresponding parts throughout the several views,

Figure 1 is a longitudinal sectional view through a sound producing device or crier illustrating one embodiment of my present invention;

Fig. 2 is a top plan view, certain of the parts being broken away;

Fig. 3 is a detail sectional view taken on the line 3—3 of Fig. 1;

Fig. 4 is a plan view of the dished sheet metal plate or wall, the sound producing element and the attaching means therefor being omitted;

Fig. 5 is a detail plan view of the sound producing element, and

Fig. 6 represents plan and edge views of the attaching member for the sound producing element.

For the purpose of illustrating one practical application of my present improvements, in the accompanying drawings, I have shown a well known type of sound producing device or crier such as is used in dolls, but it will become apparent as this description proceeds that in so far as my new reed construction is concerned it is applicable as well to other devices differently constructed or designed for other purposes or uses.

As shown in Fig. 1, the sound producing means is enclosed within a tubular casing or shell 5 having suitably formed heads 6 and 7 respectively, applied to its opposite ends, the head 7 being perforated for the escape of sound therethrough. To the other end of the casing wall 5, one end of a tubular flexible bellows wall 8 is suitably fixed, the other end of said tubular wall being provided with a weighty gravity movable head indicated at 9. As herein shown, this head consists of a heavy cast metal disc provided with the annular flange 10 at its outer edge, the body wall of said disc preferably being outwardly dished or of concavo-convex form as shown and centrally provided with an opening 11 therethrough of suitable area for the escape of sound.

The other end edge of the flexible bellows wall 8 is adapted to be fitted within the flange 10 on the head 9 and is frictionally clamped and securely held against the inner face of said flange by the marginal flange 13

formed upon the dished sheet metal plate 12. This dished body section of the plate extends within the surrounding flange 13 so that when assembled with the head 9, the concave side of said plate is opposed to the inner concave face of the body wall of the weighty head.

The sheet metal bellows clamping member may be readily stamped or formed by means of suitable dies, and the dished portion 12 thereof includes an inner circular plane section 14. The stamping dies are provided with suitably shaped parts to produce a diametrically extending outwardly struck part in the section 14 to thus provide a relatively shallow recess 15 on the inner side thereof, one end of which has a circular enlargement 16. In this stamping or forming operation, an opening 17 is cut through the metal sheet in concentric relation with the enlarged end 16 of the recess and a longitudinally extending channel 18 is also formed by outwardly pressing the metal from the plane of the base wall of the recess 15. At one end of this channel, the opening 19 is cut, thereby separating the wall of the channel from the body of the sheet metal plate and providing the egress end of the channel opening upon one side of the plane of said plate.

The sound producing element shown in detail in Fig. 5 consists of a thin vibratory strip of sheet metal cut to provide a relatively wide body section 20 and a narrow tongue 21 extending longitudinally from one end of said body section. At its other end the body section is circularly enlarged as at 22 and provided with an opening 23 therein. This sound producing element is adapted to be arranged in the recess 15, the wide body portion 20 extending across substantially the full width of said recess and the opening 23 in the end thereof registering with the opening 17. This body section 20 of the plate also extends longitudinally over the egress end of the channel 18 while the narrow tongue 21 extends over the ingress side of said channel, said tongue being of such width relative to the channel as to slightly overlap upon the side edges of the latter.

The sound producing element is permanently secured in attached relation to the dished sheet metal plate by means of the member illustrated in Fig. 6 of the drawings. This member consists of a resilient sheet metal strip 24 having a circular enlargement 25 at one end of approximately the same diameter as the circular end 22 of the sound producing element. This enlarged end of the plate 24 has a concentric tubular stud 26 stamped therefrom and this stud is adapted to be inserted through the registering openings 23 and 17. By means of suitable die members, pressure is then applied to the closed end of said stud so as to swage the same outwardly as indicated at 27 in Fig. 1

of the drawings, and clinch the same upon the outer side of the wall of the recess 15. The part of the plate 24 extending from the enlarged end 25 thereof is slightly curved longitudinally and terminates in an angularly bent flange 28 which is adapted to exert a resilient bearing pressure upon the sound producing element at the juncture of the tongue 21 thereof with the body portion 20. Thus, this resilient metal plate serves to definitely locate the fulcrum of the vibratory free end or tongue 21 of the sound producing element, thereby limiting the range of vibratory movement and thus determining the pitch of the sound produced.

It will be apparent that by producing the reed channel, the sound producing element and the attaching member therefor in the form of very simple metal stampings which can be quickly assembled in their proper cooperative positions, the manufacturing cost of such sounding reeds will be relatively small. It will be noted that as in my prior invention, the use of adhesives, thread bindings or other means heretofore employed for fixing the vibratory sound producing element in its operative position are eliminated and said sound producing element is held positively in definite relation to the ingress side of the air receiving channel. In this connection, it will be noted that the clinching stud 26 on the end of the attaching member, positively prevents any possibility of the separation of said member or of the sound producing element from the sheet metal wall, and the body part 20 of the sound producing element fitting closely between the opposite side edges of the recess 15 prevents turning movement of the sound producing element on said stud, thus obviating the obvious lateral displacement of the vibratory tongue 21 of said element with respect to the side edges of the channel 18. Therefore, in the operation of the device when said tongue is vibrated by air under pressure entering the ingress side of the channel 18, sound of the predetermined tonal pitch will always be produced. It is further to be noted that by reason of this new reed construction, it may be operatively arranged within a dish shaped weighty head which is comparatively shallow so that in the application of my invention to criers and similar devices, the sound producing means may be housed or contained within a casing of comparatively short length. However though, I have illustrated my new reed construction as used in connection with a cylindrical type bellows, it will be understood that the said construction can also be employed in connection with the forge type bellows or with any other means whereby a flow of air may be caused to pass through the channel 18. I have herein described a form and construction of the sev-

eral elements which I have found to be entirely satisfactory in practical use. Nevertheless it is to be understood that as to such details the essential features of my present improvements might also be incorporated in various other alternative structures, and I accordingly reserve the privilege of resorting to all such legitimate changes therein as may be fairly embodied within the spirit and scope of the invention as claimed.

I claim:

1. In a sounding reed, a wall having a channel therein opening upon opposite sides of said wall for the ingress and egress of air, a sound producing element having a free vibratory end portion impeding the ingress of air to said channel, and a resilient member having a part coacting with said wall and said element to fixedly secure the latter to the wall and also having a second part spaced from said first named part and contacting with said element to constitute a yieldable fulcrum bearing for the vibratory end portion thereof.
2. In a sounding reed, a wall having a channel therein opening upon opposite sides of said wall for the ingress and egress of air, a sound producing element having a free vibratory end portion impeding the ingress of air to said channel, said wall and said element having registering openings, and a resilient member having a part extending through said openings and interlocked with said wall to secure said element thereto and also having a second part spaced from said first named part and contacting with said element to constitute a yieldable fulcrum bearing for the vibratory end portion thereof.
3. In a sounding reed, a wall having a channel therein opening upon opposite sides of said wall for the ingress and egress of air, and said wall in spaced relation to one end of said channel being provided with an opening, a sound producing element extending longitudinally of the channel having a free vibratory end portion impeding the ingress of air thereto, and the other end of said element having an opening registering with the opening in said wall, and a resilient member extending longitudinally of said sound producing element having a stud disposed through said registering openings and interlocked with said wall to secure the sound producing element thereto, and said member also having a second part spaced from said stud longitudinally of said element and contacting with the latter to provide a yieldable fulcrum bearing for the vibratory end portion thereof.
4. In a sounding reed, a wall having a channel therein opening upon opposite sides of said wall for the ingress and egress of air and said wall also provided with a recess surrounding the ingress side of the

channel, a sound producing element positioned within said recess and having a free vibratory end portion extending longitudinally thereof and impeding the ingress of air to said channel, said element having another portion contacting with the opposite side edges of the recess to prevent angular displacement of said element relative to the channel, and a resilient member having a part interlocked with said wall and coacting with the other end of said sound producing element to prevent longitudinal shifting movement of the latter, said member extending longitudinally of said element and having a second part spaced from the first named part contacting with said element and providing a yieldable fulcrum bearing for the vibratory end portion thereof.

5. In a sounding reed, a stamped sheet metal wall having a part projected from the plane thereof to form a channel opening upon the opposite sides of said wall for the ingress and egress of air and said wall also provided with an opening at the egress end of the channel, a sound producing element having a vibratory end portion impeding the ingress of air to said channel and provided with an opening in its other end registering with the opening in said wall, and a member extending longitudinally of said element having a stud on one end positioned through said openings and interlocked with said wall to secure said element thereto, and said member also having a resiliently yieldable portion in contact with said element at a point spaced longitudinally thereof from said stud to constitute a yieldable fulcrum bearing for the vibratory end portion of said element.

6. In a sounding reed, a stamped sheet metal wall having a part projected from the plane thereof to form a channel opening upon the opposite sides of said wall for the ingress and egress of air and said wall also provided with an opening at the egress end of the channel, a sound producing element having a vibratory end portion impeding the ingress of air to said channel and provided with an opening in its other end registering with the opening in said wall, a sheet metal strip extending longitudinally of said element having a tubular stud stamped from one end thereof and extending through said openings, said stud being swaged upon said wall into interlocking connection therewith to secure said strip and the sound producing element to the wall, and said resilient strip at its other end contacting with said element in spaced relation to the stud to provide a yieldable fulcrum bearing for the vibratory end portion of said element.

7. In a sounding reed, a stamped sheet metal plate having a part projected from the plane thereof to form a shallow elongated recess at one side of said plate and the

base wall of said recess at one end having a longitudinally extending portion struck from the plane thereof to provide a channel opening upon opposite sides of said wall for the ingress and egress of air and said base wall of the recess at its other end having an opening therethrough, a sound producing element in said recess having a part closely contacting with the side edges thereof and provided with a relatively narrow vibratory end portion extending over the ingress side of the channel and impeding ingress of air thereto, the other end of said element having an opening therein registering with the opening in said wall, and a member having a part engaged through said openings and interlocked with the wall to secure said element in said recess and said member also having a second part spaced longitudinally of said element from the first named part and engaged therewith to provide a fulcrum bearing for the vibratory end portion of said element.

8. In a sounding reed, a stamped sheet metal plate having a part projected from the plane thereof to form a shallow elongated recess at one side of said plate and the base wall of said recess at one end having a longitudinally extending portion struck from the plane thereof to provide a channel opening upon opposite sides of said wall for the ingress and egress of air and said base wall of the recess at its other end having an opening therethrough, a sound producing element in said recess having a part closely contacting with the side edges thereof and provided with a relatively narrow vibratory end portion extending over the ingress side of the channel and impeding ingress of air thereto, the other end of said element having an opening therein registering with the opening in said wall, and a resilient metal strip

also arranged in said recess extending longitudinally of said element and provided at one of its ends with a stud engaged through said openings and interlocked with said wall to secure said strip and the sound producing element thereto, and said strip at its other end contacting upon said element and providing a yieldable fulcrum bearing for the vibratory end portion thereof.

9. In a sounding reed, a stamped sheet metal wall having a part projected from the plane thereof to form a channel opening upon the opposite sides of said wall for the ingress and egress of air, a sound producing element having a vibratory end portion impeding the ingress of air to said channel, a member coacting with said element to limit the amplitude of vibration, and means carried by one of said parts and coacting with means on each of the other parts to permanently secure the several parts in assembled relation.

10. In a sounding reed, a stamped sheet metal wall having a part projected from the plane thereof to form a channel opening upon the opposite sides of said wall for the ingress and egress of air, a sound producing element having a vibratory portion impeding the ingress of air to said channel, a member having a part engaged with said element to limit the amplitude of vibration thereof, said element and member extending longitudinally beyond the egress end of the channel, and one of said parts having integrally formed means projecting at an angle to the plane thereof and co-acting with each of the other parts to permanently secure said parts in assembled relation.

In testimony that I claim the foregoing as my invention, I have signed my name hereto.

LEO J. GRUBMAN.
